PRESSURE MEANS FOR HANDKERCHIEF MACHINES

Gustave A. Anderson, New York, N. Y., assignor to The International Handkerchief Mfg. Co., New York, N. Y., a corporation of New York

Application April 15, 1946, Serial No. 662,282

10 Claims. (Cl. 112—203)

1

This invention relates to automatic apparatus for making handkerchiefs and the like and more particularly to means for regulating and controlling the advance of the handkerchief through hemming devices so that the corners of the finished article will be square.

The invention is especially adapted for use in connection with handkerchief making apparatus of the general type shown and described in United States Patent No. 2,053,257. In that patent an apparatus is illustrated and described for automatically producing handkerchiefs in finished form from a web of material, the longitudinal edges of which preferably have already been hemmed.

In the description of the machine and its operation, the material is fed into the rear of the machine (right end of Fig. 1) and the finished handkerchiefs are removed from the forward end or front of the machine (left end of Fig. 1).

Briefly, the general plan of operation of the apparatus disclosed in that patent is as follows. The web material, previously hemmed on its longitudinal edges before it enters the apparatus from the side, is gripped and approximately the required amount to form a handkerchief is drawn transversely across the apparatus. The exact length for a handkerchief is then adjusted by producing a suitable amount of slack in the web portion. The blank is then clamped along its ends and cut off, and while it is still held in its cut position, the first fold is given to the unhemmed or raw edges. The blank is then moved longitudinally of the machine by blank feeding mechanism and as it is moved its raw edges are further folded by suitable hem formers. At the forward end of the apparatus are two sewing machines. The blank feeding mechanism advances the blank substantially to the sewing machines and an auxiliary feed mechanism then moves the blank the remainder of the distance to the sewing machines which sew both hem folded edges simultaneously. The handkerchief is then complete.

Several improvements in the blank feeding mechanism and in the auxiliary feed mechanism have now been made the subject of new applications and part of those improvements will also be disclosed herein in describing a preferred embodiment of the present invention. The pending applications to which reference is made are Serial No. 643,880, filed January 28, 1946 now Patent 2,449,044 dated Sept. 14, 1948, and Serial No. 647,784, filed February 15, 1946 now Patent 2,451,648 dated October 19, 1948.

2

As the blanks, hemmed on their front and back edges, are advanced by the blank feeding mechanism and auxiliary feeding mechanism to the sewing machines, as will be described, the two side edges of the blanks are folded into hems. The hem folding is completed just before the blanks reach the sewing machines which then stitch the hems to complete the article. Because of differences in the type, kind, weave, and cut of the cloth used, it has been found to be difficult in the patented apparatus to make handkerchiefs whose corners are uniformly square.

The present invention has as a principal object the provision of adjustable pressure means which engage each blank as it advances and thus insures that the corners of the finished article will come out square.

A broad object of the invention is the provision of means for adjusting and controlling the pressure on the hem fold just prior to stitching so as to cause the corners of the finished handkerchief to be squared.

These means may preferably be comprised of two types of mechanisms, one of which engages the hem while it is being folded, and the other of which has an edge which bears against the handkerchief blank adjacent and parallel to the hem stitching line just prior to the stitching operation. It is another object of the invention to provide such means.

These and other objects and advantages of the invention will become more apparent from the following specification and claims when read in conjunction with the accompanying drawings in which:

Fig. 1 is a side elevation of the invention.

Fig. 2 is a partial plan view with certain parts omitted.

Fig. 3 is a perspective view of one of the pressure regulating and controlling mechanisms.

Fig. 4 is a side elevation of the pressure regulating and controlling unit.

Fig. 5 is a plan view of the same.

Fig. 6 is a front elevation of the same.

Fig. 7 is a sectional view taken on the line 7—7 of Fig. 5.

Fig. 8 is an exploded perspective of several of the elements comprising one of the pressure regulating and controlling mechanisms, and

Fig. 9 is an exploded perspective of the other pressure regulating and controlling mechanism.

The mechanisms which comprise the invention are located at the forward end of the apparatus for making handkerchiefs and consequently only the forward end of such apparatus is shown.

In order to understand the structure and functions of the specific mechanisms comprising the invention, it is deemed necessary to describe in some detail the general structure of the forward portion of a handkerchief making machine in cooperation with which the invention preferably is employed.

Referring now to Figs. 1 and 2, reference numeral 11 indicates generally the main frame of the apparatus which frame is of rectangular box-like outline and includes vertical uprights such as 12 and 13 and horizontal members such as 14 and 15 (see the plan view, Fig. 2). Suitably supported above the frame are parallel spaced supports 16 and 17 for the handkerchief blank as it is moved forwardly toward the two sewing machines 18 and 19.

It is to be understood that the rear portion of the apparatus (to the right of the broken lines in Figs. 1 and 2) may be similar to the rear portion of the apparatus shown in United States Patent No. 2,053,257 to which reference has already been made. That rear portion forms no part of the present invention, but for adequate understanding of the invention it should perhaps be mentioned that such rear portion receives a web of handkerchief material whose side edges have been hemmed; cuts off blanks of a length suitable for handkerchiefs (allowing for hems); and then disposes each blank on the spaced parallel supports 16 and 17 in a position to be moved forwardly (to the left in Figs. 1 and 2). It should also be mentioned that when so disposed on the supports 16 and 17, the raw or unhemmed edges of each blank are in alignment with the parallel supports 16 and 17 and that each blank is provided with a slack portion intermediate the supports.

By the time each blank has reached that portion of the apparatus shown in Figs. 1 and 2, its raw or unfinished edges have been given a preliminary fold so as to be ready for further hem folding. The supports 16 and 17 are provided with hem folders 20 and 21 which engage the edges and fold them into hems as each blank is moved forwardly toward the sewing machines 18 and 19.

The means for moving each blank forwardly to the sewing machines 18 and 19 is comprised of a blank feeding mechanism, generally indicated by the reference numeral 22, and an auxiliary feeder, generally designated as 23.

The blank feeding mechanism 22 consists of a pair of endless chains 24 disposed in vertical planes directly above the parallel hem folders 20 and 21. These chains carry gripper feet 25 adapted to engage each blank and press its edges against the supports 16 and 17. As the chains are rotated, the gripper feet will, consequently, move the blank forwardly toward the sewing machines. Since both chains and their associated mechanism are similar, only one has been illustrated.

The main frame of the apparatus supports a pair of rear brackets such as 26 (Fig. 1) one on each side horizontal member 14, 15. These brackets 26 are connected by cross bars such as 27. The main frame also supports a pair of forward brackets, such as 28, which are connected by a cross bar 29.

The rear brackets 26 each have a rearwardly extending arm 30 bifurcated to receive a journal block 31 for a transverse shaft 32. Mounted on this shaft 32 are two large sprockets, such as 33. The shaft 32 at one end has a smaller sprocket 34 mounted thereon which sprocket 34 is suitably

connected as by a chain 35 to be driven periodically from a power source (not shown).

The forward brackets 28 carry a transverse shaft 36 and on this shaft 36 are two sprockets 37 such as 31. These sprockets 37 are mounted for free rotation about the shaft 36.

Referring to Fig. 1 it will be seen that each rear large sprocket 33 is connected by an endless chain 24 with its corresponding forward small sprocket 37. As previously indicated each chain 24 is thus disposed in a vertical plane, the planes being disposed respectively above and in alignment with the spaced parallel hemmers 20 and 21 (Fig. 2).

Each chain 24 is provided with two triangular link members 38 each carrying a lateral pivot stud 39 on which is pivotally mounted a gripper foot 25. A spring 40 connected to each stud 39 has a portion which bears against an edge of the gripper foot 25 thus urging the gripper foot in a direction away from the chain 24. The inner end of each gripper foot 25 is provided with a lateral extension 41, the purpose of which will be presently described.

Disposed adjacent each rear sprocket 33 is a cam member 42 which may be supported by an arm 43 secured to the cross bar 27 which connects the rear brackets 26. Each cam member 42 is disposed in a plane to be engaged by the lateral extensions 41 on the inner ends of the gripper feet 25.

Disposed adjacent each forward sprocket 37 is a rigid cam 9. These cams 9 likewise are disposed in planes to be engaged by the lateral extensions 41 on the inner ends of the gripper feet 25.

It should now be evident that as the sprockets 33, 37 are rotated the endless chains 24 will travel thereabout and that each chain, during a part of its path of travel, will move forwardly in a straight line directly above one of the hemmer folders 20, 21. During this part of its path of travel, one of the gripper feet 25 will bear down on a handkerchief blank and move it forwardly toward the sewing machines.

As each gripper foot 25 approaches the forward end of its path of travel, the lateral extension 41 on its upper end strikes the cam 9, the surface of which is designed to effect a pivoting of the gripper foot about the pivot stud 39, thus raising the gripper foot upwardly from the handkerchief blank.

Likewise, as each gripper foot moves around a rear sprocket 33 in a clockwise direction, the lateral extension 41 on its inner end strikes the surface of cam 42. The cam is so designed as to keep the gripper foot in a raised position until the gripper foot moves to the position shown at the right end of Fig. 1, whereupon the spring 40 will urge the gripper foot into engagement with a handkerchief blank disposed on the supports 16 and 17.

It will be seen from Fig. 1 that the apparatus just described does not move the handkerchief blank to a position directly beneath the presser feet 45 of the sewing machines. Each blank must be accurately positioned beneath the presser feet 45 of the sewing machines and for this purpose the invention employs the special auxiliary feeder mechanism 23 which will now be described.

The auxiliary feeder mechanism 23 includes a pair of pusher arms 46, 46', mounted on a shaft 47 (Figs. 1 and 2) comprising a part of a swinging frame which includes side uprights 48 and 48' which are connected by the transverse shafts 75, 47, 49 and 50, the upper shaft 50 being sup-

ported at its ends (Fig. 2) by the forward brackets 28 so that the frame may swing about the axis of shaft 50.

The side upright 48 is provided with a rearwardly extending arm 51 which is connected by a pivotal joint 52 to an operating rod 53. This rod 53 extends downwardly to a cam mechanism (not shown) which raises and lowers the rod 53 periodically to rock or swing the frame. A spring 54 (Figs. 1 and 2) secured at one end to the rearwardly extending arm 55 and at its other end to one of the front brackets 28 maintains the rod 53 in engagement with the cam mechanism.

One end of the rod 47 (Fig. 1) has a rearwardly extending arm 56 secured thereto. The arm 56 is provided with a roller 57 adapted to engage an arcuate shaped cam member 58 carried by an arm 59 secured to one of the forward brackets 28. A spring 60 secured at one end to the rearwardly extending arm 56 and at its other end to the side upright 48 constantly urges the roller 57 into engagement with the cam member 58. Therefore, any movement of the lever 59 should raise or lower lever 56 on swinging upright 48. As this lever 56 is secured to shaft 47, any movement of lever 56 is transmitted to the pusher arms 46, 46', by means of the pusher lifting levers (not numbered) which raise the pusher arms 46, 46' by means of a projecting pin on each of the pusher arms. The pusher arms 46, 46' are loose on the rod or shaft 47 and are held downwardly by the spring (not numbered).

Each of the pusher arms 46, 46' is provided with a nose piece 61 which is disposed principally in a vertical plane. Each nose piece 61 is bent at a right angle to its vertical edge thus forming a flat edge portion 62 at its lower plane extending laterally at right angles from the arm (46 or 46'). The vertical edge portion of 61 extends forwardly from edge portion 62, terminating in a blunt end 63, the bottom edge of which is on a slightly higher plane than is flat edge portion 62.

The arrangement described is such that just as the gripper feet 25 carried by the chains 24 (Fig. 1) reach their most forward position and are raised from the handkerchief blank which they have advanced, the pusher arms 46, 46' slide over the advancing edge of the blank until the forward edges of the edge portions 62 of the nose pieces 61 engage the transverse forward hem at the stitching line thereon. Continued forward movement of the pusher arms will then push against the hem and move the handkerchief blank forwardly to a position directly beneath the presser feet 45 of the sewing machines 18 and 19.

The presser feet 45 are operated by mechanism (not shown) so as to be raised just at the proper time. Such mechanism forms no specific part of the present invention but reference is made to U. S. Patent No. 2,053,257 for a showing of such mechanism.

When each blank has been delivered to the exact same position beneath the presser feet of the sewing machines, the pusher arms 46, 46' are raised and moved rearwardly ready for the next advancing blank. It will be noted that the path of movement prescribed by the pusher arms is controlled by the movement of the swinging frame and also by the engagement of the roller 57 against the cam surface 58, the latter being so formed as to assure an even distance of nose piece 62 on pusher 46 above the blank as the uprights 48, 48' of the swinging frame move to their rearward position.

Since the movement of each blank by the pusher arms is not effected until the edge portions 62 of the nose pieces 61 engage the inside edge of the hem of the blank, it will be clear that each blank will be advanced to the exact same location regardless of the position of the blank at that point where the gripper feet 25 carried by the chains 24 are disengaged from the blank.

It should also be clear that as the nose pieces 61 slide forward their blunt nose portions 63 will, in the first instance smooth down the advancing hem edge of the blank.

As previously indicated, the raw or unhemmed side edges of the blank have, during forward movement, been folded ready for hemming. The sewing machines, operating simultaneously, consequently stitch the side hems, whereupon the handkerchief is completed.

Turning now to the instant invention, it has been found that because of differences in the type, kind, weave, and cut of the cloth used, it has been difficult to provide finished handkerchiefs whose corners are uniformly square. The problem was given considerable study and it has now been determined that the formation of corners which are uniformly square can be assured by employing the pressure controlling and regulating means which will now be described.

In Figs. 3 to 8, inclusive, there has been illustrated a pressure regulating and controlling device. One of such devices is located directly to the rear of each of the presser feet 45 of the sewing machines. One of such devices will be described. With reference to Figs. 3 to 8, inclusive, reference numeral 64 represents a plate which is secured to the plate 65 on which the handkerchief blank is supported as it moves from the hem folder 21 to the presser foot 45 of the sewing machine.

Adjustably secured to the plate 64 by means of the screw 66 is a small block 67 having an elongated slot 68 therein (see Figs. 3 and 8). The block 67 is also provided with a transverse hole 69 (Fig. 8) for receiving a hinge pin 70 which is used to hinge to the block a pressure member 71.

The pressure member 71 is perhaps best shown in Fig. 8 and is comprised of a main body portion having a bifurcated end provided with transverse aligned holes 72 therein to receive the hinge pin 70.

The other end of the pressure member 71 (see Figs. 5, 6 and 7) is provided on its under surface with a sheet metal member 73 having a curved downwardly protruding edge portion 74. As will be clear from Figs. 6 and 7, and as will be described more in detail later, this downwardly protruding edge portion 74 is adapted to engage the edge of the handkerchief blank 75 adjacent and parallel to the stitching line of the hem.

The pressure member 71 is provided with an upstanding stud 76 to receive a helical spring 77 the upper end of which is engaged in a socket portion 78 of a screw 79. The screw is threadedly supported by a small bracket 80 which is secured to the plate 64 and from Figs. 3, 4, 6, and 7, it should be evident that the pressure exerted by the spring 77 on the pressure member 71 can be adjusted by turning the screw 79 and that the adjustment may then be set by means of the knurled nut 81.

The pressure member 71 (see Figs. 3, 4, 5, and 6) is also provided with a forwardly extending arm 82 which is secured to the upper surface of the pressure member 71 by means of the screw 83 (Figs. 3 and 5). The forward end of the arm 82 has a small opening therein which threadedly re-

ceives a screw 84, the position of which may be set by means of the lock nut 85. In operation, the lower end of the screw 84 rests on the upper surface of the presser foot 45 of the sewing machine.

It should now be apparent that by turning the screw 19, the pressure on the handkerchief blank 75 exerted by the downwardly protruding edge 74 of member 73 carried by the pressure member 71 can be adjusted. It has been found that if this pressure is properly adjusted, the handkerchiefs when completed will have uniformly square edges. Moreover, it will be noted that when the presser foot 45 is raised, it will, because of the arm 82, lift with it the pressure member 71 causing the latter to swing on its hinge pin 70. The reason why the pressure member 71 is raised in conjunction with the presser foot 45 is to allow the unstitched hem of the advancing blank to be inserted under the presser foot with no pressure on the hem. A pressure on the hem would cause a drag and would consequently give a distorted front hem.

From Figs. 6 and 7, it will be seen that the folded edge of the handkerchief blank 75 as it moves forwardly is guided by the inner edge 86 of the plate 64 and as the handkerchief blank reaches the forward end of the pressure member 71, the downwardly protruding edge 74 confines the hem fold with the protruding edge exerting a downward pressure on the handkerchief blank closely adjacent and parallel to the inner edge of the hem fold.

Each of the pressure regulating and controlling mechanisms described may be, and are preferably, supplemented by other pressure means which are specifically illustrated in Figs. 1, 2, and 9. Such means is specifically comprised of an arm 87 which is mounted on a transverse shaft 100, the upper portion of the arm being provided with a foot 88 having a felt pad 89 which extends upwardly through a slot 90 in the hem folder 21 so as to engage the underside of the handkerchief blank. The upwardly exerted pressure of the felt pad 89 against the handkerchief blank can be regulated. The reference number 91 represents a coil spring which surrounds the shaft 100, one end of the coil spring engaging the arm 87 and the other being secured to a collar 92. It will be apparent that the spring 91 will urge the arm upwardly. The tension of the spring can be regulated by turning the collar 92 and then securing it to the shaft 100 by means of the set screws 93.

Also secured to the shaft 100 by a set screw is the hooked arm 94, the hook portion of which is adapted to engage (Figs. 1 and 9) the laterally extending lug 95, on the arm 87. Since the position of the hooked arm on the shaft 100 can be adjusted, it will be appreciated that the position of the arm 97 can thus be adjusted accurately.

The shaft 100 (see Figs. 1 and 2) is provided with a rearwardly extending arm, 96, the end of which is secured by the spring 97 to the main frame 11 of the apparatus. Also mounted on the shaft 100 is another arm 98 which is secured by a rod 99 to mechanism (not shown) for periodically raising the rod so as to lower the felt pad from its engagement with the handkerchief blank.

It will be understood that one arm 87 is provided beneath each of the hem folders 20 and 21 so that each edge of the handkerchief blank as it advances may have pressure applied to it.

In operation, this portion of the invention is actuated by raising rod 99 and arm 98 thereby

lowering the arms 87 and felt pads 89 until the handkerchief blank 75 has been moved forwardly in the hem folders 21, 22, past the slots 90 provided in the supports 16, 17 for the felt pads. The rod 99 is then moved downwardly thus causing the arm 87 to swing upwardly so that the felt pads 89 project into the slots 90 in the supports 16, 17 and engage the under surface of the handkerchief blank 75 exerting pressure against the blank and the bottom of the hem folders 21, 22.

As indicated, the pressure exerted on the handkerchief blank by means of the felt pads can be accurately regulated and controlled.

While either of the two sets of pressure regulating and controlling devices may be employed alone, it has been found that in many instances, depending on the cloth used, more accurate and satisfactory results are obtained by regulating and controlling the pressure on the handkerchief blanks at two points, namely, rearwardly adjacent the pressure feet and also farther back namely at the point where the felt pads exert their pressure on the blanks. The use of these devices if properly regulated can insure square corners in the finished handkerchiefs regardless of the type of cloth used.

It is to be understood that changes in structure and arrangement of the parts may be effected within the scope of the invention which is only to be limited in accordance with the language of the following claims.

I claim:

1. An apparatus for making handkerchiefs and the like and including a pair of spaced sewing machines, support means for said blanks, means for hem folding opposite side edge portions of handkerchief blanks and advancing said blanks on said support means to said sewing machines which simultaneously sew the opposite side edge portions into hems, the forward and rear edges of said blanks having been previously hemmed, mechanism disposed rearwardly adjacent the sewing machines for exerting downward pressure on the side edge portions of the blanks adjacent and parallel to the side hem folds, means for adjusting the downward pressure of said mechanism, mechanism disposed rearwardly of the sewing machines for exerting upward pressure on the side edge portions of said blanks, and means for adjusting the amount of said upward pressure.

2. An apparatus for making handkerchiefs and the like, means for hem folding opposite side edge portions of handkerchief blanks and for advancing said blanks forwardly toward sewing machines which sew said side edges into hems, the forward and rear edges of the blanks having been previously hemmed, a frame, support means on said frame for the side edge portions of each blank as it is advanced toward the sewing machines, means for pressing said side edge portions of each blank downwardly against said support means and for moving the blanks forwardly along said support means, auxiliary means for advancing the blanks beneath the presser feet of the sewing machines, pressure mechanism having a downwardly protruding edge for engaging said side edge portions of each blank adjacent and parallel to the side hem folds, and means for adjusting the pressure exerted by said pressure mechanism, whereby the corners of the finished article will be squared.

3. A pressure device for machines for sewing handkerchief blanks, comprising, a flat support for a side edge portion of the blanks, a plate disposed on said support rearwardly adjacent the

presser foot of the sewing machine, the side edge of said plate forming a guide for the outer edge of the side hem fold of each blank, a member pivotally mounted on a line parallel to and spaced from said side edge of said plate, said member having a portion extending over said side edge, said portion having a downwardly extending edge parallel to said side edge and adapted to engage the upper surface of each blank adjacent the inner edge of the side hem fold of the blank, a bracket secured to said plate and having a part extending over said member, a screw carried by said part, and a spring disposed between said screw and said member for exerting downward pressure on said member.

4. A pressure device for machines for sewing handkerchief blanks, comprising, a flat support for a side edge portion of each blank, a plate disposed on said support rearwardly adjacent the presser foot of the sewing machine, the side edge of said plate forming a guide for the outer edge of the side hem fold of the blank, a member hinged to said plate on a line parallel to and spaced from said side edge of said plate, said member having a portion extending over said side edge, said portion having a downwardly extending edge parallel to said side edge and adapted to engage each blank adjacent and parallel to the inner edge of the side hem fold of the blank, a bracket secured to said plate and having a part extending over said member, a screw carried by said part, a spring disposed between said screw and said member for exerting downward pressure on said member, an arm secured to said portion and extending forwardly over the presser foot of the sewing machine, and a screw in said arm adjustable to engage an upper surface of the presser foot, whereby the arm and said hinged member will be raised when the pressure foot is raised to permit a blank to be inserted beneath the pressure foot with no pressure on the hem.

5. In a machine for sewing the side hem of a handkerchief blank, the forward and rear hems of the blank having been previously hemmed, a sewing machine provided with a presser foot, a hem folder spaced rearwardly from the presser foot, a support for the blank intermediate the hem folder and the presser foot, a plate mounted on said support rearwardly adjacent the presser foot the inner side edge of said plate forming a guide for the outer edge of the side hem fold as the blank moves to the presser foot, a member hingedly mounted with respect to said plate on a line parallel to and spaced from said side edge, said member having a portion extending over said side edge of said plate, said portion having a downwardly extending edge parallel to said side edge and adapted to engage the blank adjacent and parallel to the inner edge of the side hem fold, a bracket secured to said plate and having a part extending over said member, a screw carried by said part, and a spring disposed between said screw and said member for exerting downward pressure on said member.

6. An apparatus for making handkerchiefs and the like and including a pair of spaced sewing machines, support means for said blanks, means for hem folding opposite side edge portions of the blanks and for advancing the blanks on said support means to said sewing machines which simultaneously sew the opposite side edge portions into hems, the forward and rear edges of said blanks having been previously hemmed, mechanism disposed rearwardly adjacent the sewing machines for exerting downward pressure

on the blanks adjacent and parallel to the side hem folds, means for adjusting the downward pressure of said mechanism, mechanism disposed rearwardly of the sewing machines for exerting upward pressure on the side edge portions of said blanks, and means for adjusting the amount of said upward pressure, said means for exerting upward pressure including a shaft, an arm mounted on said shaft, a pad carried by said arm, and spring means for urging said arm and pad upwardly.

7. An apparatus for making handkerchiefs and the like and including a pair of spaced sewing machines, support means for said blanks, means for hem folding opposite side edge portions of the blanks and for advancing the blanks on said support means to said sewing machines which simultaneously sew the side edge portions into hems, the forward and rear edges of said blanks having been previously hemmed, mechanism disposed rearwardly adjacent the sewing machines for exerting downward pressure on the blanks adjacent and parallel to the side hem folds, means for adjusting the downward pressure of said mechanism, mechanism disposed rearwardly of the sewing machines for exerting upward pressure on the side edge portions of said blanks, and means for adjusting the amount of said upward pressure, said means for exerting upward pressure including a shaft disposed below said support means, a pair of arms rotatably mounted on said shaft, a pad carried by the free end of each arm, said support means having slots therein to permit the pads to engage the blank, spring means for urging said arm and pads upwardly, and means for adjusting the tension of said spring means.

8. Pressure means for an apparatus for forming and stitching a hem on the side edge of a handkerchief blank or the like, said apparatus having a support for the blank hem folding means, and a sewing machine for stitching the hem, said pressure means comprising a shaft disposed below said support, an arm rotatably mounted on said shaft, a pad carried by said arm, said support having a slot therein for said pad to permit the pad to engage the underside of the blank, a spring engaging said arm to urge it upwardly, and means for adjusting the tension of said spring.

9. Pressure means for an apparatus for forming and stitching a hem on the side edge of a handkerchief blank or the like, said apparatus having a support for the blank hem folding means, and a sewing machine for stitching the hem, said pressure means comprising a shaft disposed below said support, an arm rotatably mounted on said shaft, a pad carried by said arm, said support having a slot therein for said pad to permit the pad to engage the underside of the blank, a coil spring surrounding said shaft, a collar on said shaft, one end of said spring engaging said collar and the other end said arm, and means for securing said collar to said shaft.

10. Pressure means for an apparatus for forming and stitching a hem on the side edge of a handkerchief blank or the like, said apparatus having a support for the blank hem folding means, and a sewing machine for stitching the hem, said pressure means comprising a shaft disposed below said support, an arm rotatably mounted on said shaft, a pad carried by said arm, said support having a slot therein for said pad to permit the pad to engage the underside of the blank, a coil spring surrounding said shaft, a

11

collar on said shaft, one end of said spring engaging said collar and the other end said arm, means for securing said collar to said shaft, and means adjustably secured to said shaft for limiting the upward movement of said arm and said pad.
